UNITED STATES PATENT OFFICE.

JAMES V. WASHBURN, OF WATERBURY, CONNECTICUT.

STUD MEMBER OF GLOVE OR GARMENT FASTENERS.

SPECIFICATION forming part of Letters Patent No. 738,708, dated September 8, 1903.

Application filed November 12, 1902. Serial No. 130,947. (No model.)

To all whom it may concern:

Be it known that I, JAMES V. WASHBURN, a citizen of the United States, residing at Waterbury, in the county of New Haven and State of Connecticut, have invented an Improvement in Stud Members of Glove or Garment Fasteners, of which the following is a specification.

My invention relates to the well-known stud-and-socket form of glove and garment fasteners in which the parts are adapted to be snapped into connection, and my invention relates particularly to coacting parts of the stud member of the fastener, and the object thereof is to economize metal and reduce the area or thickness of the structure.

My invention consists in the combination, with the post and collet of the stud member, of a spring-head and eyelet, each having peripheral interlocking parts in the same plane, both of which parts are simultaneously engaged and firmly held by the collet. The post passes through the flexible material and through the eyelet, and the closed end of the post is advantageously spread or upset, so as to engage the eyelet at its outer open end to hold the parts securely to the flexible material.

In the drawings, Figures 1 and 4 are vertical sections representing forms of my invention. Fig. 2 is a plan of the parts in Fig. 1, partially broken open, so as to clearly show the structure. Fig. 3 is a plan of the eyelet shown in Figs. 1 and 2 separate. Fig. 5 is a plan of the form shown in Fig. 4, with part broken open, so as to clearly show the structure; and Fig. 6 is a plan of the eyelet, alone shown in Figs. 4 and 5.

The spring-head *a* is stamped out of a piece of sheet metal and cupped up to shape, and the radial portions thereof are preferably provided with segment-feet having radial opposite edges. The eyelet *b* is made with a base or flange of liberal area, the same being provided with peripheral notches, leaving radial projections *b'*. These notches are adapted to receive the segment-feet *a'* of the spring-head *a*, and the extreme diameter of the eyelet at the edges of the flange agrees with the diameter of the spring-head *a* at the periphery of the segment-feet, so that when the spring-head and the eyelet are brought together the segment-feet of the spring-head and the ra-

dial projections of the eyelet-flange match and occupy the same plane, interlocking with one another, so that there is only one thickness of metal in the plane of the interlocking parts. 55

The collet *c* has a central aperture larger than the post *d*, and the outer portion or edge of the collet *c* in its normal condition is turned up as a flange and occupies a position at right angles to the main flat portion of the collet and the same receives the spring-head and eyelet, and this upturned edge or flange of the collet is overturned upon the segment-feet of the spring-head and the projections of the eyelet, so as to grip said parts to connect them and to form of the spring-head, the eyelet, and the collet a connected structure. 60

The post *d* passes through the flexible material *e*, and the flange of the post rests against one surface of said flexible material. The connected structure hereinbefore described comes against the opposite surface of said flexible material and the post passes through the eyelet. In connecting the post to this structure the closed end of the post is slightly spread in any desired manner and by any suitable instrumentality, so that the same is upset as a rivet within the spring-head and against the open upper end of the eyelet, as shown in Figs. 1 and 4, in which position the various parts are held firmly and securely to the flexible material. 75

In the form of my invention shown in Figs. 4, 5, and 6 the feet of the spring-head are made in an elliptical form, and the metal at the ends of the radial portions of the head connecting the same with the feet portions 2 are given a sharp or right-angle bend, and in the flange portion of the eyelet are made elliptical perforations 3, slightly larger than and adapted to receive the elliptical feet portions of the spring-head, and the flange edge of the collet *c* in this form, as in the form hereinbefore described, is overturned down upon the flange of the eyelet and the feet of the spring-head, so as to hold the same together and to the collet and form of the spring-head, the eyelet, and the collet a connected structure, in which said feet and flange are in the same plane. 80

In Figs. 2 and 5 I have broken open a part of the overturned flange of the collet, so as to

show clearly the construction of the spring-head and the eyelet.

From the foregoing description and the drawings it will be apparent that in this invention there is at the overturned flange of the collet only a single intervening thickness of metal. Therefore the stud member of the glove and garment fastener is more compact in form and the meeting-surfaces of the garment not only appear to come closer together, but actually do come closer together, so that there is less appearance of a gap between the parts that are connected, because of a reduced thickness of metal.

I claim as my invention—

1. In a glove and garment fastener, the combination with a post and collet, of a spring-head and eyelet having interlocking peripheral parts engaged by the collet so that there is only one thickness of metal in the plane of the interlocking parts engaged by the overturned flange of the collet.

2. In a glove and garment fastener, the combination with a post and collet, of a spring-head having segment-feet at the ends of its radial portions and an eyelet having a flange with notched portions receiving said feet, the one part interlocking with the other and received in and held by the overturned edge of the collet, said parts being in the same plane

with only one thickness of metal in the grasp of the collet.

3. In a glove and garment fastener, the combination with a post passing through the flexible material with a flange upon one side, a collet having an aperture for the post and lying against the other side of the flexible material and having a peripheral edge adapted to be overturned, of a spring-head with segment-feet terminations to its radial portions, the opposite edges of which are on radial lines, an eyelet having a flange agreeing in extreme diameter with that of the spring-head and having its periphery notched to receive the segment-feet of the spring-head and the intermediate projections of the eyelet created thereby formed with edges upon radial lines, said parts fitting one another and interlocking and occupying the same plane as one thickness of metal received in the collet and connected thereto by overturning the edge of the collet so that within the grasp of the collet there is only one thickness of metal.

Signed by me this 5th day of November, 1902.

JAS. V. WASHBURN.
